PULLER

Phillips H. Clarke, Washington, D. C., and Richard M. Cutts, The Plains, Va., said Cutts assignor to said Clarke

Application December 30, 1948; Serial No. 68,208

2 Claims. (Cl. 29—261)

This invention relates to pulling devices, and especially to combination jack-screw and slide hammer pullers of the type disclosed in Johnson and Clarke Patent No. 1,893,414, granted January 3, 1933, and aims generally to improve the same.

Tools of the class exemplified in the said Johnson and Clarke patent embody a tensioning and aligning rod having an extended threaded area onto which various work-engaging devices may be threaded, which rod carries a relatively heavy slide hammer element. In use of such tools the correct work engaging device has heretofore been selected and threaded onto the rod, the tool being then held in one hand while the work-engaging device is manipulated to engage the work, with the other, and the rod being then threaded through the work-engaging means into engagement with an abutment to prealign the tool with the work, provide initial pulling tension, or adjust the length of the rod, the hammer being then manipulated to augment the initial tension with a prealigned impact force to effect removal of the part.

In such tools it has been found desirable to provide the work-engaging device, when the latter comprises two or more pivoted work-engaging arms, with means for adjusting the spread of those arms to engage them firmly with the work. The provision of such adjusting means, however, has rendered it necessary to manually hold the tool in nearly aligned position with one hand during the manipulation of the arm adjusters with the other, as well as during manipulation of the tensioning rod. Due to the weight of the extended rod and hammer this has been fatiguing and has sometimes resulted in a failure of the mechanic to properly apply the tool to the work.

In addition, in most cases the aligning rod of the puller is threaded through the selected work-engaging means a substantial distance during use of the tool, and it is necessary to unscrew it many turns before the tool can be applied to other work or have other heads and adapters applied thereto.

The present invention, among other objects, aims to provide a puller tool quickly and easily adjusted to the work, and one in which the adjustment of the tool to particular jobs and the exchange of heads thereon is quickly and easily accomplished.

More specifically, the invention aims to provide a tool of the class described in which the work-engaging head is slidably adjustable to any selected position on the threaded rod and there securable in threaded relation.

The invention also aims to provide such a tool having an inexpensive and simple but effective construction. Other objects and advantages of the invention will be apparent from the following detailed description of exemplary embodiments thereof.

The invention resides in the novel features and combination of parts hereinafter described and pointed out in the appended claims.

In the accompanying drawings illustrating preferred embodiments of the invention:

Fig. 1 is a side elevation and Fig. 2 an elevation partly in longitudinal section of a puller with parts of the rod cut away.

Figs. 3, 4 and 5 are transverse sections taken, respectively, on the lines 3—3, 4—4, and 5—5 of Fig. 2 looking in the directions indicated by the arrows.

Fig. 6 is a perspective view of the tool of Fig. 1.

Fig. 7 is an end view of a modified form of head.

2

attaching split-threaded element and securing means therefor.

In the illustrative embodiment shown in Figs. 1-6, the puller comprises a screw-rod 10 threaded for a substantial distance adjacent its inner end. The rod in the form shown is provided with a head 11, formed to provide for application of a turning force thereto. In the form shown the rod-head 11 is of hexagonal cross-section to receive a turning wrench, and has a transverse aperture 12 therethrough to receive a turning bar or the like. In the form shown a slide-hammer element 13 is slidably mounted on the rod 10 and at one end of its stroke abuts against the rod-head 11.

The work-engaging means or head 14 may be of various types, certain of which are illustrated in the above mentioned Johnson and Clarke patent. Preferably several different types of heads are provided in a puller set to adapt it to a variety of work. Thus while the tool is herein shown provided with a head 14 of the three-way yoke type, it is to be understood that the invention in its broader aspects is not limited to this type of work-engaging means, and may be provided with one or more selectable heads.

In accordance with this invention, the work-head 14, shown as comprising a control spider member 14a and pivoted work-engaging arms 14b, comprises a central hub member 15 which is bored to slidably fit over the threaded portion of the rod 10. Thus the head 14 may be slipped onto or from the rod 10 and may be slid therealong to any desired position.

Releasable means is also provided for threadedly attaching the head 14 to the rod 10 when it has been slid longitudinally to its adjusted position, and to provide for setting up of the rod therethrough for applying tension and/or prealigning the slide hammer blow. In the form shown in Figs. 1-6 this means comprises a split-threaded member 16, the two halves of which close upon the threaded portion of the rod, and which is provided with means for securing it to the head 14.

In the form shown, the hub 15 of head 14, which is centrally bored to slidably fit the rod 10, has externally threaded on it a camming disc or cone 17 which engages between the rearwardly projecting tail portions of the arms 14b to spread them apart. A length of coil spring 18 embraces the rearwardly projecting tail portions to resiliently urge the arms to spread position in the arrangement shown. The arms 14b are reversible, like those shown in the Johnson and Clarke patent, but are provided with ears 19, which project outwardly in the reversed position of the arms, forwardly of their pivot points. Thus when the arms are reversed the spring may be moved to lie between the spider member 14a and the ears 19, to hold the arms in contracted position against a spreader disc or cone (not shown) which may be positioned between the arms, either on the tip 10a of the rod 10 as shown in the Johnson and Clarke patent, or otherwise.

With the arrangement shown in Figs. 1-6 it will be seen that the complete head assembly, including the camming disc 17, the spring 18 and the arms, forms a single unit through which the rod 10 may be slipped, either before or after the work-engaging unit is adjusted to the work.

As is best shown in Figs. 2 and 6, the split-threaded member or split-nut 16 is secured to the work-engaging head 14. This securing is preferably effected by the interengagement of groove and flange means 20—20a arranged on the split-threaded member 16 and the hub 15 of the head 14. The flange means, or collar, 20a, carried by the head or work-engaging means 14 is external; or male, and preferably formed integral with the yoke, spider, or body portion 14a thereof. This element, however, may be made separately and be secured to the tool heads by welding, swaging, riveting, threading or otherwise, and the flange means may be continuous or discontinuous, as desired.

Preferably as shown, the interengaging means 20—20a are formed to limit relative rotation between the split-threaded member and the head 14, as by providing a non-circular engagement or rotary abutment therebetween. In the form shown this is accomplished by providing one

member, herein the groove of the split unit 16, with at least one projecting element or stud 21, to engage an abutment means provided by the other member, herein formed by the walls of one or more slots or recesses 22 in the flange 20a carried by the hub 15. In the form shown the stud 21 is provided by a pin driven into a bored-out hole in the flange of the split-nut 16, and flush with its front face.

Where practicable, friction between the parts 20—20a, or manual or tool gripping of the sleeve 16 (as by a bar inserted in one of the holes 16a) may be relied upon to insure relative rotation of the split-nut 16 and the screw-rod 10 to assure advance thereof.

The split-nut or split-threaded member 16 is also provided with means for releasably securing it in its closed or driving relation to the rod and head. In the form of Figs. 1-6 this means comprises an internally tapered sleeve 23, adapted to frictionally fit the tapered section 24 of the split-nut 16, to be tightly engaged thereon by a slight blow. In the form shown this blow may be imparted by backing the hammer 13 against the sleeve 23, and the sleeve may be disengaged from the tapered section 24, as by inserting a wedging or prying member between the adjacent faces of the members 16 and 23, or by tapping against the inner side of a rear flange 25 provided on the sleeve 23. Due to inertia effect this arrangement cooperates effectively in the slide hammer embodiment, since after the hammer has seated the member 23, subsequent blows of the hammer 13 against the head 11 serve to tighten, rather than loosen, the engagement of the sleeve with the split member 16.

The parts of the split-nut section 16 may be movably associated in any suitable way, as by the hinge connection 26 (Figs. 4 and 6). The groove and flange arrangement 20—20a, in the form shown, tends to guide the two halves of the split thread into proper engagement with the threads of the rod 10, thus assisting the hinge 26 in maintaining proper alignment.

In the form shown, the locking sleeve 23, split sleeve 16 and camming disc 17 are provided with knurled surfaces to facilitate manual turning or holding thereof, as well as with holes 16a and 17a to receive a turning bar. The hinge 26 of the split-nut element performs not only the function of keeping the two parts together, but also acts as a guide to mutually align the female groove and flange sections 20 and the threads in the two halves of the split member. The elements 20, 20a serve not only to lock the slideable head 14 to the split nut, but also act as a guide to align the threads of the split member 16, in lieu of or supplemental to the hinge 26.

In using the tool of this invention, to free a pulling-head from the threaded rod it is merely necessary to release the split-nut 16 and slide the head along the rod. To secure a selected head to the rod it is merely necessary to slide the rod through it to the proper location, and close the split-nut in embracing relation to the head and rod.

In attaching the tool to a machine part to be removed, say a gear to be removed from a shaft end, the head assembly 14 alone, by means of the spreader 17, may first be adjusted to the part without handling of the rod and hammer at all. The rod 10 may then be quickly slipped through the positioned head and into abutting relation with the shaft end. The split-nut may then be closed about the parts and locked against spreading, after which a very few turns of the rod through the split-threaded member suffices to align the puller and apply pulling tension to the work. A quick tap of the hammer 13 against the rod-head 11 may then be employed to augment the initial pulling tension and easily moves the workpiece without tilting it and damaging the parts. Where a long draw under impact of the hammer is required, the rod 10 may be brought to bear against the shaft end between each movement of the part effected by the hammer operation, thus insuring correct alignment of the pulling force. When the part has been moved to a sufficiently loose position, it may be drawn free simply by further advancing the screw rod 10, and when the parts are to be adjusted

for a second pulling operation it will not be necessary to reverse this screwing operation, as the head may be dropped free from any part of the extended threaded area of the rod and repositioned thereon as desired.

As above mentioned the invention is not limited to the preferred form shown in Figs. 1-6. Merely by way of illustration, and without intention of limiting the invention thereto, a further exemplary form is illustrated in Fig. 7. In this arrangement the two halves of the split-nut are secured together by locking means shown as a toggle latch 30, which grips them tightly together just as it passes its dead center position, and no tapered members are required.

Having described preferred embodiments illustrative but not restrictive of the invention, what we claim is:

1. A puller tool comprising a combined screw and slide hammer rod having an extended threaded area and having a hammer impacted head at one of its ends, a work-pulling head formed to slide longitudinally along the threaded area of said rod, a slide hammer mounted on said rod between said hammer impacted and work-pulling heads, a nut closable on said threaded area, said nut having an externally split end portion facing said slide hammer, means for securing said split-nut to said work-pulling head and means for locking said nut in its closed position, said locking means comprising an internally conical sleeve between said end portion and the slide hammer, engageable over said end portion, and tightenable thereover by manipulation of said slide hammer, said nut constituting the sole means for securing said pulling head to said threaded rod, so that extended threaded movement of the parts is unnecessary while on engagement of said last named means, impacts of the hammer against the hammer impacted head cause the rod to pull on the work-pulling head to cause the latter to pull on the work.

2. A puller tool comprising a combined screw and slide hammer rod having an extended threaded area and having a hammer impacted head at one of its ends, a work-pulling head formed to slide longitudinally along the threaded area of said rod, a slide hammer mounted on said rod between said hammer impacted and work-pulling heads, a split-nut closable on said threaded area above said work-pulling head, engaging means carried in part by said work-pulling head at one end thereof and in part by said split-nut at its bottom end thereof for detachably securing said split-nut to said work-pulling head, and releasable locking means for locking said split-nut in its closed position, said nut constituting the sole means for securing said pulling head to said threaded rod, so that extended threaded movement of the parts is unnecessary while on engagement of said last named means, impacts of the hammer against the hammer impacted head cause the rod to pull on the work-pulling head to cause the latter to pull on the work.
